MATERIAL APPLICATOR FOR PLANOGRAFIC PRINTING MACHINES

Franklin E. Curtis, Willoughby, Ohio, assignor to
Addressograph-Multigraph Corporation, Cleve-
land, Ohio, a corporation of Delaware

Application September 10, 1938, Serial No. 229,242

10 Claims. (Cl. 101—148)

This application is a continuation in part of my copending application No. 147,507, filed June 10th, 1937, and its division No. 174,396, filed November 13th, 1937.

5 The present invention is especially concerned with improvements in the automatic application of repellent and ink to the printing cylinder of a planographic printing machine. The object of the invention is to provide a simple mechanism which is reliable in operation, and not likely to get out of order, for causing a proper transference of the repellent from its fountain to the plate carrying drum, and the ink from its fountain to said drum.

15 The invention includes features concerned with the ductor rolls of the repellent and ink application, for causing the ductor rolls to make accurate contact with the fountain rolls and the other rolls with which the ductors coat to transfer material effectively to the printing roller. A feature of the mechanism is that it enables a dwell of the ductor roll in contact with the co-operating roll while the mechanism continues its movement to operate the fountain roll. In the case of the repellent application, where the difficulty has been to transfer the very liquid repellent from the fountain to the plate, my mechanism holds the ductor roll positively in engagement with the fountain roll while the same mechanism operates to turn the fountain roll, thus effectively carrying the liquid to the ductor roll. In the case of the inking mechanism, where the viscosity of the ink allows the fountain roll to feed plenty of ink to the ductor roll, I cause the ductor roll to dwell against the roll to which the ink is to be delivered, and hold it positively in such engagement to obtain effective transfer, notwithstanding the viscosity of the ink, and I use the opposite stroke of the same mechanism as it returns the ink ductor to turn the fountain roll.

To obtain proper contact of the ductor rolls throughout their length with the respective rolls with which they coat, and at the same time hold 45 the ductor rolls in proper longitudinal position, I mount each ductor roll in a yoke pivoted centrally, on an axis normal to the roll axis, to a swinging operating device which is connected to the operating mechanism. This insures the ductor roll promptly engaging the roll with which it contacts throughout the length of the ductor roll at an equalized pressure.

50 My invention relating to the above features, is hereinafter more fully described in connection

with the present embodiment thereof, as illustrated in the drawings.

In the drawings, Fig. 1 is a substantially centrally located longitudinal section for a printing machine, embodying my improved material applicator system; Fig. 2 is a fragmentary side elevation thereof, showing the ductor-operating mechanism; Fig. 3 is an enlarged detail of a portion of the ductor-operating mechanism; Fig. 4 is a plan of the machine, partly broken away to illustrate more clearly the internal construction of the machine; Fig. 5 is a vertical sectional view taken along the line 5—5 of Fig. 4, showing the mounting of the ductor roll for the repellant, 10 the mounting of the ink ductor roll being similar. 15

In the drawings I have illustrated my improved material applicator system in a planographic printing machine of the type shown and described in my copending application heretofore referred to. In the present application this 20 printing machine has been simplified in many details for ease of illustration. However, reference may be had to the copending application, referred to, for a more complete disclosure of such machine.

In the drawings of the present application there is shown a frame, comprising a pair of side plates 11 and 12, tied together by suitable cross members, some of which are generally indicated at 10. Rotatably journalled in this frame are a 30 pair of horizontally extending shafts 15 and 16, the former supporting a transfer roll 18 and the latter a pattern roll 19, which carries a printing member B. The shafts 15 and 16 may be mounted in eccentric bushings, not shown, to permit 35 them to be adjusted, one with the other.

Rotatably journalled on a shaft 20, below the transfer or offset cylinder 18, is a platen roll 21. The platen roll shaft 20 may be supported by the frame members 11 and 12 in a manner to 40 permit adjustment and alignment of the roll with the offset cylinder. A suitable sheet feed table 22 is mounted on the frame to enable work sheets to be fed into the bite of the platen and offset rolls 21 and 18, respectively.

45 The offset roll may be provided with a suitable gripper and ejector mechanism, illustrated in my copending application 147,507, heretofore mentioned, to receive the paper sheet ahead of the bite of the printing couple and eject or strip 50 such sheet from the roll following the passing of the paper between the printing couple, guiding such printed sheet beneath a paper guide 23 into a suitable receptacle 24 carried by the frame.

The present invention is especially concerned

with the material applicator system for first applying an ink repellent to the planographic or similar type of printing plate, and subsequently applying planographic ink to such repellent coated plate, so that only the image portions of the printing plate will carry ink to the transfer roll 18, and thereby to the work sheet.

The moistening or ink repellent fluid is stored in a removable fountain or tray 30, which is supported on lugs or ears 31 extending from the frame plates 11 and 12. This fluid is removed from the fountain 30 by a fountain roll 32. The fountain roll is drivingly mounted on stub shafts 33a and 33b, which are journalled in respective frame plates 11 and 12. This roll is intermittently driven, as will be hereinafter described.

The moistening or repellent fluid is transferred from the fountain roll 32 to a form roll 34 by a ductor roll 35. The ductor roll 35 is rotatably mounted on a shaft 36, supported by upstanding arms of a yoke 37, Fig. 5. This yoke is pivotally secured to a second yoke 38, the downwardly depending arms of which are pivotally mounted on respective frame members 11 and 12, as at 39. This pivotal connection and its advantages will be hereinafter more fully described. The ductor roll 35 is intermittently rocked from contact with the fountain roll 32 into contact with the form roll 34, as hereinafter explained.

The form roll 34 of the repellent applicator system is rotatably supported as by a shaft 40, suitably carried so as to have a proper pressure against the printing plate. For simplicity of illustration, no adjustment of this shaft is shown in the drawings, and no means, except the resilience of the roll-covering for supplying pressure, but this can be effected, if desired, by mounting this roll in a removable frame spring pressed toward the pattern drum, as shown in my applications referred to.

Both the form roll 34 and the ductor roll 35 are provided with absorptive fabric coverings to enable them to convey the fluid from the fountain roll to the printing plate.

Ink is supplied to the moistened pattern by an inking mechanism, best shown in Fig. 1. This inking mechanism comprises the usual fountain 50, carried by the frame members 11 and 12. This fountain is provided with a fountain roll 51, against which the usual fountain plate 52 is adjustably positioned by a plurality of adjusting screws, one of which is shown in Fig. 1 at 53. Ink is transferred from the fountain roll 51 to a transfer roll 54 by a ductor roll 55. This ductor roll is rotatably mounted on a shaft 56, supported by a pair of upstanding arms of a yoke 57. This yoke is pivotally secured as at 58, as will be hereinafter more fully described, to a second yoke 59, the depending arms of which are pivotally secured to respective frame members 11 and 12, as at 60. The support of the ink ductor is therefore similar to that of the repellent ductor, as shown in Fig. 5. The ductor roll 55 is rocked periodically about the pivots 60 into alternate engagement with the fountain roll and the transfer roll, by mechanism to be hereinafter more fully described.

The ink transfer roll 54 is journalled on a shaft 61. This transfer roll transfers the ink from the ductor roll 55 to a form roll 62, which is journalled on a shaft 63. The shaft 63 is suitably carried in such manner that the roll may be removed when desired, but in use is spring-pressed against the printing plate B on the plate cylinder 19. For simplicity of illustration, no means, other than the resilience of the roll itself, are shown

for obtaining pressure, but the means set out in my prior applications mentioned may be employed, if desired.

The ink distributor roll 54 is driven in synchronism with the pattern drum 19. As indicated in Fig. 1, a gear 65 is drivingly secured to the pattern drum and meshes with a pinion 66 which in turn drives a gear secured to the distributor roll 54. The drum 19 may be driven from a motor M, the driven pulley 67 of which is connected with a pulley 68 by a drive belt 69. The pulley 68 is secured to a stub shaft 70, journalled in the frame plate 12. Also drivingly secured to this stub shaft is a spur gear 71, which meshes with a gear 72 of a compound gear member rotatably mounted on a stud 73. The other gear 74 of this gear member meshes with and drives the spur gear 75, which drives the pattern drum, 19, as well as to the distributor roll 54. The ink fountain roll 51 is driven from a cam 100 mounted on the transfer roll 18, which, in turn, is driven by the pattern drum gear 65 through a gear 101, Fig. 4.

As indicated in Fig. 2, the cam 100 on the end of the offset drum coats with a roller on a rock arm 104. This arm is mounted on a rock shaft 105, journalled in the frame plate 11. Mounted on the other end of the rock shaft is a lever 106. The upper arm of this lever operates the repellent applicator and the lower arm the ink applicator, as about to be described.

The upper end of the rocking lever 106 is provided with a cam extension 107, which is adapted to coat with a roller 108, carried by an arm 109 extending upwardly from the yoke 38, which carries the yoke 37 supporting the repellent ductor roll 35. The ductor roll is normally retained against the repellent form roll 34 by a suitable spring indicated at 110, attached to the arm 109, but when the upper end of the lever 106 is swung toward the left (Fig. 2) the nose of the cam extension 107 engages the roller 108 and positively shoves it toward the left, until the ductor roller comes into a pressure-contact against the fountain roll 32, as indicated in Fig. 3. At this time a face 112 of the cam extension 107, which is concentric about the axis of the rock shaft 105, reaches the roller 108 which is now positioned so that the concentric surface may ride beneath the roller, as indicated at the broken lines in Fig. 3. The effect of this is to hold the ductor roller for a considerable time with desired pressure against the fountain roll, while the arm 106 continues its movement to perform the operation of positively turning the fountain roll, as is about to be explained.

While the concentric surface 112 enables the lever 106 to swing freely about the positioned roller 108, the roller 108 cannot shift its position since it can only swing about the pivot 39 as a center. Accordingly, the ductor roll remains held positively against the fountain roll, notwithstanding the continued movement of the arm 106.

As heretofore explained, the ductor roll has a soft, absorbent covering, so that its surface is yielding, and hence by properly adjusting the roller 108 the pressure of the ductor roll against the fountain roll may be nicely regulated. This adjustment of the roller 108 is enabled because this roller is mounted on a pin 114, which is eccentric of the axis of the stud 115 which connects the pin to the arm 109. This stud 115 has an angularly formed portion 116 for the application of a wrench to turn the stud on its own axis, thereby changing the position of the roller 75

pin 114, as indicated by the dotted lines in Fig. 3.

The feature of positively holding the repellent ductor roll in pressing engagement with its fountain roll, while the latter is turned, is an important characteristic of my invention, as it insures effective transfer of the repellent liquid from the fountain roll to the ductor roll. On the return stroke of the lever 106, the spring 110 effectively holds the ductor roll against the form roll to continue the transfer to the form roll, and thence to the printing plate.

The upper arm of the rocking lever 106 is connected by a link 120 to a rock lever 121, journalled on the shaft 33a of the repellent fountain roll 32. This shaft carries a ratchet wheel 122 (Fig. 2) and the rock lever 121 on its lower arm carries a pawl 123, spring-pressed toward the ratchet wheel. Accordingly, the rocking of the lever 106 operates to give successive partial rotations to the repellent fountain roll, while the ductor roll is firmly held in contact therewith.

An adjustment is provided whereby the pawl 123 may be regulated to advance the ratchet wheel, and therefore the fountain roll 32, a varying distance equivalent to a selected number of ratchet teeth, for each revolution of the offset drum 18. This adjustment, as shown in Fig. 2, is accomplished by positioning a cam plate 125 about the axis of the fountain roll shaft 33a, causing the cam portion 126 of the plate to engage a pin 127 carried by the pawl 123. This disengages the pawl from the ratchet wheel at a predetermined point, thus determining the distance the ratchet wheel is to be advanced. A suitable detent, such as the spring 128, engages one of a plurality of notches 129 in the cam plate to maintain it in an adjusted position. A lateral extension 125a of this cam plate may project through the frame and cover plates to facilitate the manipulation of the cam. If desired, a similar arrangement may be used to regulate the feed of the ratchet of the ink fountain roll 51, heretofore described.

The ductor roll 55 of the ink repellent applicator is likewise driven by the offset drum 18 through the cam 180 and the rocking lever 106. The lower arm of this rocking lever is connected by the link 130 (Fig. 2) to a lever 131 pivoted on the shaft of the inking fountain roll 51. This lever, at its upper end, is formed with a cam surface 132, which, for the most part, is concentric about the axis of the fountain roll shaft. This cam surface coats with a roller 135 on an arm rising from the yoke 59, which carries the yoke 51 supporting this ductor roll. The construction in this regard is similar to that heretofore described for the repellent ductor roll. If desired, the roller 135 may be adjusted in a manner similar to the roller 108. A spring 136 normally maintains the ductor roll in contact with the fountain roll 51, but the cam 132 on its movement in the left-hand direction (Fig. 2) swings the ductor roll into contact with the proper pressure against the ink transfer roll 54 and causes it to dwell in that position while the lever 131 is continuing its movement.

The lever 131 on the axis of the ink fountain roll shaft carries a pawl 137 spring-pressed against the ratchet wheel 138, attached to the fountain roll shaft. The pawl and ratchet face in such direction that the movement toward the left (Fig. 2) which carries the movement of the link 130 to the left and carries the ductor roll into engagement with the transfer roll, causes the pawl to click idly over the ratchet teeth,

whereas the return of the link toward the right, which frees the ductor and enables its spring 136 to bring it against the fountain roll, positively turns the fountain roll, its left-hand portion moving upwardly to contact with the ductor roll. 5

It results from the above construction that the ink ductor is held by its spring in contact with the ink fountain during the turning of the fountain roll, and thus readily picks up a sufficient quantity of ink, and thereafter the ductor roll is 10 shifted and positively held in contact with the transfer roll until the ink is transferred to that roller. I have found that this makes a very satisfactory transference of ink from the fountain to the transfer roll and thence to the printing plate. 15

To enable the convenient mounting and removal of either ductor roll from its yoke 51 or 57, I prefer to use the clip device illustrated at 140, in Fig. 5. That is to say, the left-hand end 20 of the yoke has a round hole in its upper arm for the reception of the projecting end of the ductor roll shaft, while at the right-hand end there is an open notch 141 to receive the shaft. Beyond the notch is the clip plate 140 having an outwardly curved upper end. As shown in Fig. 5, this clip plate is held in position by a compression spring 142, which is compressed between the plate and a head 143 on a stud carried by the yoke arm and projecting freely through a flared 30 opening in the clip.

By finger pressure against the upper end of the clip 140, that end of the ductor roll is released, enabling such end to be lifted free of the yoke arm and thus the roller may be drawn out of the 35 other arm of the yoke. Conversely when the roller is to be put into place, the projecting end of the shaft is passed through the round hole in the left-hand end (Fig. 5) of the yoke arm, and the shaft at the other end is pressed down on the curved upper end of the clip 140. This cams the clip away from the yoke arm and allows the sealing of the shaft in registration with the opening in the clip, whereupon the clip springs back into the position shown in Fig. 5. 45

From the description given, it will be seen that I have provided an efficient material applicator system for a planographic or similar printing machine, which system includes a liquid repellent applicator mechanism and an ink applicator mechanism, both of which mechanisms are driven from the offset or transfer roll, and each of which mechanisms includes a readily removable ductor roll which, when in place, is pivotally mounted on an axis normal to itself, to enable it to 50 align with either its fountain roll or its distributor roll, regardless of misalignment between the axes of any of the rolls. This pivotal mounting, together with the driving mechanism for oscillating the ductor rolls and causing them to dwell 55 in positively controlled pressure contact with their fountain and distributor rolls, results in an effective and even application of repellent and ink to the printing plate. 60

I claim:

1. In a printing machine, the combination of a plate cylinder, a form roll, a fountain roll, a movable ductor between the fountain roll and form roll, mechanism for operating the movable ductor comprising a swinging lever having a concentric cam acting on a swinging ductor support, whereby the ductor may remain in contact with the member it engages for a relatively prolonged period. 70

2. In a printing machine, the combination with 75

5. a fountain roll having a ratchet, a lever having a pawl to coact with the ratchet, an operating lever linked to the ratchet lever, and a cam on the operating lever adapted to engage an adjustably positioned member on the swinging support.
10. 3. In a printing machine, the combination of a swinging support, a ductor roll carried thereby, a cam pivoted on an axis different from that of the swinging support, said cam having a concentric surface, and an adjustable member on the swinging support which the cam engages, whereby the cam may swing the support for a distance and thereafter hold it in its swung position.
15. 4. In a printing machine, the combination with an ink fountain roll, an ink transfer roll, an intermediate ductor roll mounted on a swinging support, a ratchet wheel on the fountain roll, and a lever having a pawl to coact with the ratchet wheel, said lever having a cam adapted to engage 20. a member on the swinging support to hold the ductor roll positively in engagement with the receiving roll.
25. 5. In a planographic printing machine, the combination with a repellent supply system having a fountain roll, a ductor roll and a roll to receive material from the ductor, a rocking support for the ductor roll, a ratchet drive for the fountain roll, a rocking lever linked to the ratchet drive, and a cam on the lever engaging the rocking support of the ductor roll.
30. 6. In a planographic printing machine, the combination of a plate cylinder, an ink feed and a repellent feed for the plate cylinder, each of said feeds including a movable ductor roll mounted on a swinging support, two pivoted arms having cam portions to engage the two ductor roll supports respectively, a rock shaft connected with the respective arms and a cam for operating the rock shaft.
35. 7. In a planographic printing machine, the

combination with a repellent supply system and an ink supply system, each having a fountain roll, a ductor roll and a roll to receive material from the ductor roll, ratchet drives for the two fountain rolls, an intermediately pivoted rocking lever linked at one end of one ratchet drive, and at the other end to the other ratchet drive, a cam on the lever engaging the movable support of one of the ductor rolls and a cam on one of the ratchet drives engaging the movable support of the other ductor.

8. In a printing machine, the combination with a pair of rolls of an interposed ductor, a swinging support for the ductor comprising a yoke having a pair of arms occupied by the ductor roll shaft, one of the arms having a hole to receive the shaft, the other arm having a notch, a movable spring clip adjacent the latter arm and having a hole to receive the ductor roll shaft at that end, said clip being held in position by a spring and adapted to be swung outwardly away from its arm to receive or release the ductor roll shaft.

9. In a printing machine, in combination with a fountain roll and a material receiving roll, of an interposed ductor roll, and mechanism adapted to move the ductor roll into contact with one of said rolls and interpose a non-yielding member positively blocking the ductor roll against return movement for an appreciable time while said mechanism continues its movement and performs another operation.

10. The combination of a fountain roll, a ductor roll, mechanism for moving the ductor roll into contact with the fountain roll and positively holding it there for an appreciable time by means independent of friction or resiliency, and means by which said mechanism during said holding time continues its movement to turn the fountain roll.

FRANKLIN E. CURTIS. 46
